UNITED STATES PATENT OFFICE.

FREDERICK TSCHIRNER, OF NEWARK, NEW JERSEY, ASSIGNOR TO RICHARD G. WAGNER, OF NEW YORK, N. Y.

ROTARY KILN.

1,292,927.

Specification of Letters Patent. Patented Jan. 28, 1919.

Application filed April 13, 1917. Serial No. 161,852.

To all whom it may concern:

Be it known that I, FREDERICK TSCHIRNER, a citizen of the United States, residing at Newark, in the county of Essex and State 5 of New Jersey, have invented certain new and useful Improvements in Rotary Kilns; and I do hereby declare the following to be a full, clear, and exact description of the invention, such as will enable others skilled in 10 the art to which it appertains to make and use the same.

The present invention concerns an apparatus for the heat treatment of materials, and is particularly designed for use in connection with the heat treatment of a mixture 15 of greensand, lime sand and salt, in accordance with the process of my copending application filed of even date herewith.

In the accompanying drawing, Figure 1 20 shows a vertical section of the lower end of the rotary kiln and the connections at the said lower end, and Fig. 2 shows a horizontal section taken on the line 2—2 of Fig. 1, looking downwardly.

25 In said drawings 10 is a rotary kiln of any desired structure, rotated by a suitable mechanism commonly employed in the art, and which accordingly it is not necessary to illustrate. The lower end of the said rotary 30 kiln projects into a housing 11, which may be lined with heat resistant and heat insulating material 12, to prevent undue loss of heat by radiation.

35 At 13 is illustrated a burner for heating the material being fed through the rotary kiln, this being for example a gas, coal or oil burner of any approved type. Surrounding the burner and projecting toward the open mouth of the kiln 10 is a sleeve 40 14, which may be made of refractory tile or similar material, the function of which is to choke the flame and prevent the same from spreading, so that a comparatively long and narrow flame will be produced, 45 which need not come into direct contact with the material being calcined in the rotary kiln. Suitable valves will be provided for regulating the air and gas or air and oil supplied to the burner.

50 At 15 I have illustrated another burner, which if desired may be of a much smaller size than that shown at 13, this burner being for the purpose of heating the material after passing through the rotary kiln. The 55 material calcined in the kiln 10 drops into

the receptacle 16, provided with a gate 17 at the bottom for discharge, below which is placed a suitable conveyer 18 for carrying away the discharged material to grinding and leaching apparatus. The gate 17 60 may be normally kept closed, or may be normally kept slightly open, in order to allow the material to slowly feed from the compartment 16 to the conveyer, and to retain a relatively large body of material in 16. 65

Receptacle 16 may be made of any suitable fire resistant material, such as tile, and the function of this receptacle is to retain the calcined material for a considerable time, in a heated condition, and the burner 70 15 may be regulated so as to maintain the material in the compartment 16 at the same temperature at which it leaves the kiln 10, or at slightly higher or slightly lower temperatures, as desired. 75

The products of combustion from the burner 15 pass around the receptacle 16, may be directed forward and backward by baffles 21 having openings 22, and may be discharged at 19, and flow into the kiln 10, 80 or these products of combustion may be separately drawn off, if so desired.

What I claim is:

1. An apparatus of the character described comprising an inclined rotary kiln, 85 a burner located opposite the mouth of said kiln for heating the same, a receptacle at the outlet end of said kiln for collecting and holding the material coming from said kiln, and means for indirectly applying heat to 90 such material, for maintaining its temperature, while out of contact with direct heating means, and while avoiding rapid currents of gases in contact with the material.

2. In a calcining apparatus, an inclined 95 rotary kiln, a burner located opposite to and at a distance from the mouth of said kiln, a hollow sleeve surrounding the mouth of said burner, and extending toward said kiln, a receptacle at the outlet end of said 100 kiln, for collecting and storing the material coming from said kiln, and means for keeping the material hot, without contact of heating flame therewith, and without contact of the material with gas currents caused 105 by the products of combustion.

3. An inclined rotary kiln connected at its lower end with a receptacle, and means for heating said kiln comprising a burner located at the lower end thereof, for project- 110

ing a flame into the said kiln, in counter-current with the solid material being calcined therein, and external heating means only for said receptacle.

5 4. An inclined substantially cylindrical rotary kiln, a burner for directing a flame into the lower end thereof, said kiln being connected at its lower end with a receptacle,

and means for heating said receptacle, said receptacle being inclosed in a heat insulated 10 housing, the material in said receptacle being protected from currents of gases.

In testimony whereof, I affix my signature.

FREDERICK TSCHIRNER.
